UNITED STATES PATENT OFFICE.

EDWARD J. CLARKE AND PHILIP DEWITT, OF SCRANTON, PENNSYLVANIA.

SAFETY DEVICE.

No. 893,053.

Specification of Letters Patent.

Patented July 14, 1908.

Application filed July 16, 1907. Serial No. 384,058.

To all whom it may concern:

Be it known that we, EDWARD J. CLARKE and PHILIP DEWITT, citizens of the United States, residing at Scranton, in the county 5 of Lackawanna and State of Pennsylvania, have invented certain new and useful Improvements in Safety Devices, of which the following is a specification, reference being had to the accompanying drawings.

10 Our invention relates to improvements in automatic safety appliances for railways, and more particularly to the one set forth in Patent No. 845,727, granted to us February 26, 1907.

15 The principal object of the present invention is to improve and simplify such apparatus or appliances and render them more durable, reliable and economical in operation.

20 Another object of the invention is to provide in a fluid pressure safety appliance of this character which applies the brakes by opening the train pipe of the air brake system, means whereby the pressure in the 25 train pipe will be only slightly reduced when the safety appliance is operated, thus enabling the system to be quickly restored to its normal condition so that the brakes may be released and the train started in a much 30 shorter time than if the pressure in the train pipe was entirely reduced.

A further object of the invention is to provide a safety appliance of this character which may be set to obtain the "service", 35 the "emergency", or other application of the air brakes, and which is so arranged that when it is set to obtain any other application of the air brakes except the "emergency" application, the latter will be obtained when 40 the engineer's brake valve is operated to produce a further reduction of pressure in the train pipe.

With the above and other objects in view, the invention consists in the combination of 45 devices and the novel features of construction hereinafter described and claimed, and illustrated in the accompanying drawings, in which

Figure 1 is a diagrammatic view of our improved safety apparatus; Fig. 2 is a longitudinal section through the main operating cylinder; Fig. 3 is a section through the pressure reducing valve; Figs. 4 and 5 are

sectional views taken in planes at right angles, through the double cock or valve; 55 Fig. 6 is a sectional view through the controlling valve; Fig. 7 is a longitudinal section through the throttle lever; Fig. 8 is a detail view of the trip device, and Fig. 9 is a detail view of a modified form of the invention. 60

The present embodiment of our invention is especially designed for use upon a steam locomotive and is adapted to automatically stop the train by closing the throttle valve 65 and actuating the air brakes, when the train passes a signal set to indicate danger or a switch that is improperly set or whenever it is desired to stop the train at a certain point either regularly or in case of emergency. 70

In the drawings 1 denotes the throttle lever which is pivoted at 2 and connected to the throttle valve as at 3. This lever is adapted to be locked to a rack segment 4 by a spring pressed dog or pawl 5 mounted 75 upon the lever and adapted to be retracted from engagement from the rack in the usual manner by a rod 6 connected to a hand piece on the free end of the lever.

The throttle lever is adapted to be unlocked and actuated in a direction to close the throttle by the movement of a piston 7 in the main operating cylinder 8. The rod 9 of said piston passes through a suitable stuffing box in one end of the cylinder and 80 is pivotally connected to one end of a rod or link 10 having at its other end a wedge shaped head or dog 11. The rod 10 and its head 11 are adapted to work between two rollers 12, 13 arranged upon the throttle 90 lever. The roller 12 has a stationary axle or pivot while the pivot or axle of the other roller 13 is carried by a sliding bar 14 which is attached to the locking dog or pawl 5, as clearly shown in Fig. 7. 95

Fluid under pressure for the purpose of actuating the piston 7 may be admitted into the cylinder 8 from any suitable source but we preferably employ compressed air and take it from the air brake system, as shown 100 in the drawings. The inlet pipe 15 for the cylinder preferably leads from the pipe 16 between the main reservoir 17 and the engineer's brake valve 18 of the air brake system. This inlet or supply pipe 15 has arranged in it a controlling valve 19 preferably

in the form of a rotary plug valve, as more clearly shown in Fig. 6. The casing of the valve has a small relief or discharge port 20 and the rotary body or plug of the valve has 5 a main transverse port 21 adapted to co-act with the bore of the casing and a small radially arranged port 22. These ports 20, 21, 10 22 are so arranged that when the valve is in its normal position, shown in Fig. 6, the branch of the pipe 15 leading from the pipe or conductor 16 is closed while the other branch leading from the cylinder 8 is in communication with the atmosphere through the ports 22, 21, 20. The valve 19 has upon its 15 outer end a lever 23 which is loosely pivoted upon a slidable operating rod or element 24. The inlet pipe 15 leads to the forward end of the cylinder 8 and at the point where it connects with the same it is provided with 20 two branches 25, 26 in the latter of which is arranged a check valve 27 the purpose of which will be presently explained. At the opposite or rear end of the cylinder 8 is arranged 25 a small needle valve 29 adapted to cushion the movement of the piston 7, and also a pipe or conductor 30 having two branches 31, 32 similar to the branches 25, 26 of the pipe 15. In the branch 32 is arranged 30 a check valve 33, the purpose of which will presently appear. The pipe 30 has its other end in communication with a cylinder 34 containing a piston 35 having its rod 36 connected to a bracket or arm 37 upon the operating rod or element 24. This cylinder 34 is provided for the purpose of resetting or returning the controlling valve 19 to its normal position, as hereinafter described.

In order to notify the engineer or other attendants of the train that there is danger and that the apparatus has been operated we provide an alarm device preferably in the form of a whistle 38 of ordinary construction and arrange it upon the cylinder 8 in communication with its forward end so that it will be operated when the compressed air enters said cylinder through the inlet pipe 15. The movement of the piston 7 not only serves to successively unlock the throttle 50 lever and move it in a direction to close the throttle valve, but also to apply the air brakes, the latter being accomplished in the following manner. A conductor or pipe 39 is arranged between the train pipe 40 of the 55 air brake system and a pressure reducing valve 41, and a double valve or cock 42 is arranged to control the passage of compressed air through the two pipes or conductors 16, 39. The valve 42, as clearly shown in Figs. 60 4 and 5 comprises a casing 43 having a centrally arranged valve seat 44 for a rotary plug 45 and two transverse passages or ports 46, 47 which intersect the valve seat or bore 44 in planes at right angles to each other.

The ends of the passage or port 46 are connected to the branches of the pipe 39 and the two ends of the port or passage 47 are connected to the two branches of the pipe 16. The valve plug or body 45 is formed with two transverse ports 48, 49 the former of 65 which is adapted to co-act with the passage 46 and the latter of which with the passage 47. The ports 48, 49 are arranged in the same transverse plane so that when the port 49 aligns with the passage 47, the port 48 is 70 out of alignment with the passage 46 and vice versa, hence it will be seen that when the hand lever 50 attached to the valve plug 45 is turned through an arc of 90° the pipes 16, 39 will be alternately opened and closed. 75 The normal position of the body 45 of the double valve 42 is such that the pipe 16 is open so that the main reservoir is in communication with the engineer's brake valve and the pipe 39 is closed in order to maintain the 80 usual pressure of seventy pounds in the train pipe 40. The valve handle 50 is connected by a chain or other flexible element 51 to the rod 9 of the piston 7 so that when the latter is actuated the double valve 42 will be moved 85 to close the pipe 16 and open the pipe 39, the latter permitting the air in the train pipe 40 to exhaust through the pressure regulator 41 which may be set to close when the pressure in the train pipe has been reduced to any desired extent. The flexible chain or connection 51 also permits the resetting of the piston 7, without returning the handle of the double valve or cock 42, which latter operation would release the brakes owing to the feed of 90 air through the engineer's brake valve 18, unless the latter was set at a point other than 95 where it should be, namely, "running".

While any suitable form of pressure regulating or reducing valve may be employed at 105 the outlet end of the pipe 39 we preferably use the one illustrated in Fig. 3 of the drawings. This device comprises a cylindrical casing 52 having at one end an inlet 53 and an outlet 54 with a valve seat 55 arranged 110 about the latter and adapted to receive a valve 56 on the stem 57 of which is arranged a piston or plunger 58 to slide in the cylinder 52. The upper portion of the stem of the valve 56 slides through an adjusting nut 59 115 arranged in a threaded opening in one end or head of the cylinder 52 and adapted to have its inner end engage a washer 60 arranged on one end of a coil spring 61 which surrounds the valve stem and has its other end engaged 120 with the washer 62 which bears upon the plunger 58. It will be seen that when the pipe 39 is opened the air from the train pipe enters the cylinder 52 through the inlet 53 and forces the piston 58 in the direction to 125 unseat the valve 57 and permit of the escape of the air through the outlet 54. When the pressure has been sufficiently reduced the

spring 61 closes the valve 57 so that the pressure in the train pipe will be maintained in such reduced state.

While the pressure reducer or regulator is usually set to close when the pressure is about sixty pounds it will be seen that by adjusting the screw 59 the tension of the spring 61 may be varied to cause the valve 57 to close when the pressure has been reduced to any desired extent. It will be noted that the provision of this pressure regulator or reducer prevents the air in the train pipe from being entirely exhausted from the same, and hence enables the air brake system to be more quickly restored to its normal condition so that the brakes may be released and the train started in a very short time after the apparatus has been actuated to stop the train. While the operating rod or element 24 may be actuated by any suitable means we preferably employ that shown in the drawing, said means comprising a suitable trip 63 arranged upon the track or road bed and adapted to contact a swinging dog 64 carried by the locomotive and in the form of a lever pivoted at 65 adjacent to one of its ends so that its long end will swing downwardly and maintain it normally in a vertical position. Rollers are arranged at the opposite ends of the lever or dog 64 and the upper one is adapted to support a latch 66 pivotally connected to one end of a weighted lever or crank arm 67 arranged on a rock shaft 68 to which latter is also connected a lever or crank arm 69 that connects with the operating rod or element 24. When the parts of this operating device are in their normal position, the dog 64 supports the latch 66 and the latter holds the weighted lever 67 elevated, and as the train passes the trip 63 the latter strikes the dog 64 and swings it from beneath the latch 66 so that the weighted lever 67 drops and swings the rock shaft 68 and the lever 69. The movement of the latter actuates the rod 24 which in turn opens the controlling valve 19 to admit air into the cylinder 8.

The preferred form of the trip device 63 is shown in Fig. 8 and comprises a base 70 adapted to be arranged upon the road bed centrally between the tracks and having arranged above it two trip levers or arms 71, 72. The latter have their pivots arranged for a sliding movement in slots or openings 73 in the base and they are each actuated by coil springs 74 arranged upon their pivots. These levers are connected as at 75 and are actuated by a link or rod 76 having a slotted lower end to receive a pin upon a crank arm 77 the shaft or pivot of which latter is journaled upon the base 70. A second crank arm 78 is arranged upon the shaft or pivot of the crank 77 and is connected by a link 79 to a bell-crank 80. This bell crank is also connected at 81 to a switch point 82. When the

switch is in its proper position, the trip levers 65 are held down in an inoperative position, that is out of the path of the dog 64 on the locomotive or train, but when the switch is improperly set, the parts of the device will assume the position shown in Fig. 1 and one of the trip levers will engage and actuate the dog 64 to set in operation the apparatus upon the locomotive. By constructing the trip device in this manner and providing the springs 74 it will be seen that should the connection 75 between the switch or other device and the trip levers break the latter will be moved by said springs to their operative position. The springs further serves to reduce the shock and strain upon the levers when they are struck by the dog or any other part of a rapidly moving train. It will be understood that the trip device instead of being connected to a switch, as shown in Fig. 1, may be connected to a semaphore or other signaling device, a drawbridge or the like.

The operation and advantages of the invention will be readily understood from the foregoing description taken in connection with the accompanying drawings and the following brief statement. Assuming the parts of the apparatus to be in the normal position, and the locomotive to be moving in the direction of the arrow in said figure, it will be seen that when the dog 64 strikes the trip 63 it will release the latch 65 and the weighted lever will drop and rock the shaft 68 which through the lever 69 will actuate the operating rod or element 24 in a downward direction. The rod 24 opens the valve 19 and the air from the pipe 16 enters the cylinder 8 and forces the piston 7 from the front to the rear end of the cylinder. As said piston is actuated the wedge 11 on the rod or link 10 separates the rollers 12, 13 and 105 hence retracts the dog 5 from the rack 4 to unlock the throttle lever and then swings said lever in a direction to close the throttle valve. Said movement of the piston also causes the flexible element 51 to swing the lever 50 of the double valve 42 so that the pressure in the train pipe 40 is released through the pressure regulator 41 for the purpose of applying the air brakes. When the compressed air is admitted into the cylinder 8 the whistle or signal 38 is also sounded to notify the engineer or others of the operation of the apparatus. When the piston 7 reaches the end of its stroke the compressed air enters the branch 32 of the pipe 30, 120 passes through the check valve 33 and then passes from the pipe 30 into the cylinder 34 to actuate its piston 35 and hence the operating rod 24 which latter it restores to its normal position to close the controlling valve 19 125 and to restore the parts 64, 66, 67 of the apparatus to their normal positions. As the valve 19 is closed the supply of compressed

air is cut off and the pressure of that contained in the cylinder 34 will return the piston 7 to its original position. Said air in the cylinder 34 expands through the pipe 30 and its branch 31 into the piston 8 and then escapes from the latter through the branch 26 the check valve 27 and the pipe 15 to the valve 19 from which latter it escapes through the port 20. Thus it will be seen that all of 10 the parts of the apparatus excepting the valve 42 will be automatically returned to their normal positions. The valve 42 is restored to its normal position by hand, whereupon all parts of the apparatus will be 15 in their normal positions and ready for automatic operation. The reason for not returning the double valve 42 to its normal position automatically is that when that is done the air brakes are released owing to the passage 20 of air through the engineer's brake valve; and it will be readily seen that should the air brakes be automatically released while the train is on a grade or in any other dangerous position there would be more or less likelihood 25 of a collision or other accident. I therefore, prefer to control the double valve 42 manually. As above stated the pressure reducing or regulating valve may be set to obtain the "service", "emergency" or any 30 other application of the air brakes, but I preferably set it to secure the "service" application since there is always more or less danger attending the "emergency" application and because the latter application will be secured 35 when the engineer's brake valve is operated to produce a further reduction of pressure in the train pipe. It will be further noted that the use of this appliance upon the train does not interfere in any way with the ordinary 40 operation of the air-brake system.

Our improved safety appliance may be used upon an electric locomotive or car by substituting for the throttle lever and its co-acting parts, an electric switch 80 arranged 45 in the motive power circuit 81 and suitably connected to the piston rod 9, as shown in Fig. 9 of the drawings. The circuit breaker 81 is here shown in the form of a knife switch having its lever connected by a chain or 50 flexible element 82 to the piston rod 9. But, it will be understood that any other circuit breaker and operating connections may be substituted.

Having thus described our invention what 55 we claim is:

1. In an automatic train controlling apparatus, the combination with the train pipe of the air brake system and a pressure reducing means, of a valve for controlling communication between said train pipe and said 60 pressure reducing means, means for controlling the motive power, and a single, fluid-pressure operating means for simultaneously actuating said valve and said

means for controlling the motive power, substantially as described. 65

2. In an automatic train controlling apparatus, the combination with the train pipe of the air brake system and a pressure reducing means, of a valve for controlling communication between said train pipe and said pressure reducing means, a throttle lever, a fluid pressure cylinder, a piston therein, an operative connection between said valve and said piston and an operative connection between said piston and said throttle lever, substantially as described. 70 75

3. In an automatic train controlling apparatus, the combination with the train pipe of the air brake system, and a pressure reducing means, of a valve for controlling the communication between said train pipe and said pressure reducing means, means for controlling the motive power and means actuated by the last mentioned means for actuating said valve, substantially as described. 80 85

4. In an automatic train controlling apparatus, the combination of the train pipe of the air brake system, a pressure regulator, the throttle lever, a lock for the latter, means for controlling said lock, a valve for controlling communication between the train pipe and the pressure regulator and means for operating said lock controlling means, said throttle lever and said valve, substantially as described. 90 95

5. In an automatic train controlling apparatus, the combination of the train pipe of the air brake system, a pressure regulator, the throttle lever, a lock for the latter, means for controlling said lock, a valve for controlling communications between the train pipe and the pressure regulator and fluid pressure means for actuating said lock controlling means, said throttle lever and said valve, substantially as described. 100 105

6. In an automatic train controlling apparatus, the combination of the train pipe of the air brake system, a pressure regulator, a valve for controlling communication between the two, the throttle lever, a lock for the latter, means for successively releasing said lock and actuating said lever to cut off the motive power, a cylinder, a piston therein and connected to said valve and said means for operating the throttle lever and its lock and means for admitting fluid under pressure into said cylinder, substantially as described. 110 115

7. In an automatic train controlling apparatus, the combination of the train pipe of the air brake system, a pressure regulator, a valve for controlling communication between the two, the throttle lever, a lock for the latter, means for successively releasing said lock and actuating said lever to cut off the motive power, means for actuating said valve and said lever and lock operating means, and means for resetting the last men- 120 125

tioned operating means, substantially as described.

8. In an automatic train controlling apparatus, the combination of the train pipe of the air brake system, a pressure regulator, a valve for controlling communication between the two, the throttle lever, a lock for the latter, means for successively releasing said lock and actuating said lever to cut off the motive power, a fluid pressure means for operating said valve and said lever and lock operating means, a valve for admitting a fluid under pressure into said fluid pressure operating means, means for actuating the last mentioned valve and means for returning the last mentioned valve to its normal position, substantially as described.

9. In an automatic train controlling apparatus, the combination with the engineer's brake valve, the main reservoir and the train pipe of the air brake system, of a pressure regulator, a double rotary plug valve arranged between the main reservoir and the engineer's brake valve and between the train pipe and the pressure regulator and fluid pressure operating means for actuating said plug valve.

10. In an automatic train controlling apparatus, the combination with the engineer's brake valve, the main reservoir and the train pipe of the air brake system, of a pressure regulator, a double rotary plug valve arranged between the main reservoir and the engineer's brake valve and between the train pipe and the pressure regulator, a crank for rotating said plug valve, a fluid pressure cylinder, a piston therein and a flexible connection between the rod of said piston and the crank of the valve.

40 11. In an automatic train controlling apparatus, the combination with the engineer's brake valve, the main reservoir and the train pipe of the air brake system, of a pressure regulator, a valve casing having two sets of opposing ports arranged in different planes, the ports of one set being connected to the main reservoir and the engineer's brake valve and the ports of the other set being connected to the train pipe and the pressure regulator, a rotary valve in said casing and having two transverse ports or openings arranged in different planes to co-act with the ports in the casing, a crank upon said rotary valve, a fluid pressure cylinder, a piston therein and a connection between the rod of said piston and said crank, substantially as described.

12. In an automatic train controlling apparatus, the combination with the engineer's brake valve, the main reservoir and the train pipe of the air brake system, of a pressure regulator a valve for simultaneously closing communication between the engineer's brake valve and the main reservoir and opening communication between the train pipe and the pressure regulator, motive power con-

trolling means, and fluid pressure operating means for simultaneously operating said valve and said motive power controlling means, substantially as described.

13. In an automatic train controlling apparatus, the combination with the engineer's brake valve, the main reservoir and the train pipe of the air brake system, of a pressure regulator, a valve for simultaneously closing communication between the engineer's brake valve and the main reservoir and opening communication between the train pipe and the pressure regulator, a crank for operating said valve, the throttle lever, a lock for the latter, a fluid pressure operating means, a flexible connection between the latter and the crank of said valve, and means for successively unlocking and actuating the throttle lever connected to said fluid pressure operating means, substantially as described. 70

14. In an automatic train controlling apparatus, the combination with means for controlling the motive power and the air brakes, of a fluid pressure operating means for the same comprising a cylinder, a piston therein, 90 a fluid inlet conductor having two branches opening into one end of said cylinder a check valve in one of said branches, a valve for controlling the passage of fluid through said conductor, an operating element for said valve, 95 a second cylinder, a piston therein connected to said operating element, a conductor between said second cylinder and the opposite end of the first mentioned one, the last mentioned conductor having two branches opening into the first mentioned cylinder and a check valve in one of said branches, substantially as described. 100

15. A trip device of the character described comprising a base, toggle levers arranged above the same, a hinge connecting one of said levers to the base, a spring for elevating said hinged lever, a crank shaft a slotted link connecting the latter to the hinged connection between said toggle levers, and 110 means for actuating said crank, substantially as described. 105

16. In an automatic train controlling apparatus, the combination of means for controlling the motive power, the train pipe of the air brake system, a pressure regulator, a valve controlling communication between the train pipe and said pressure regulator, and means for simultaneously actuating said valve and the controlling means for the motive power, substantially as described. 115 120

17. In an automatic train controlling apparatus, the combination with the engineer's brake valve, the main reservoir and the train pipe of the air brake system, of a pressure 125 regulator, a valve for controlling communication between the main reservoir and the engineer's brake valve and between the train pipe and the pressure regulator, means for automatically operating said valve to open 130

communication between the train pipe and the pressure regulator and to close communication between the main reservoir and the engineer's brake valve, and means for automatically resetting said operating means, said valve being adapted to manually reset, substantially as and for the purpose set forth.

In testimony whereof we hereunto affix our signatures in the presence of two witnesses.

EDWARD J. CLARKE.
